ELECTRIC SWITCH FOR LAMP-SOCKETS, &c.

1,222,886.

Specification of Letters Patent. Patented Apr. 17, 1917.

Application filed April 14, 1915. Serial No. 21,212.

To all whom it may concern:

- Be it known that we, SHIRAS MORRIS and MONROE GUETT, citizens of the United States, and residents of Hartford, in the county of Hartford and State of Connecticut, have jointly invented certain new and useful Improvements in Electric Switches for Lamp-Sockets, &c., of which the following is a specification.
- 10 The principal object of the present invention is to provide a comparatively cheap and easily made attachment which can be readily applied by loosely fitting it to the rotary switch member and which when so applied will coöperate with the other element in efficiently and reliably opposing or preventing the formation of arcs, and this I do by forming and applying the attachment in such a way that while the connection is a loose one, 15 portions of the appliance will underlie the contacts of the rotary member in position for breaking or opposing the formation of arcs while other portions of the attachment will coöperate with the contacts for 20 holding the first mentioned portions in the described position when the rotary member is rotated. At the same time the attachment is additionally kept in its proper location by being interposed between the stationary 25 and rotary spring pressed switch members.

To these and other ends hereinafter set forth the invention stated in general terms comprises a combination of elements having the form, material and coöperation herein- 30 after described and particularly pointed out in the claims.

In the accompanying drawings, Figure 1 is a side view, drawn to an enlarged scale, with parts broken away of a socket embodying or containing features of the invention.

Fig. 2, is a similar view with parts omitted for the sake of clearness.

Fig. 3, is a top or plan view, drawn to an enlarged scale, and Fig. 4 is an edge view, 45 drawn to an enlarged scale, of an attachment constituting a feature of the invention.

Fig. 5, is a top and Fig. 6 a bottom view, drawn to an enlarged scale, of the rotary element of the switch provided with the attachment.

Fig. 7, is a transverse sectional view of the device shown in Fig. 5, and

Fig. 8 is a diagrammatic development,

drawn to an enlarged scale, of a part of the switch.

In the drawings 1 is a lamp socket, 2 is a fixed crown-tooth member having upon the inclined faces of its diametrically opposed teeth contact elements 3. Disposed centrally of this crown-tooth member is a pivot or post 6. 4 is a rotary switch member arranged to turn around the post as a center. 5 is a spring retracted pawl arm oscillatable about the post 6 and provided with a pull-chain 7. This pawl arm is afforded up and down motion by the spring 8 and its pawls are on its under-face, which is next to the rotary switch member. There is nothing new about this pawl arm and it serves to turn the rotary switch member 4 when the chain 7 is pulled. The rotary switch member is provided with depending contacts 9 and 9^a, offset as at 10 and it consists of a hub portion provided with outwardly extending arms 11 and 12. The arms 12 carry the contacts 9 and 9^a. Applied to this hub portion is a disk 13 of insulating material, notched for the passage of the offset portions 10 of the contacts and underlying the arms 11 and secured to the hub part by a crimped portion 14 thereof. The arms 11 and 12 are engaged by the pawls of the pawl arm and so the rotary switch member intermittently is driven in a direction opposite to that in which the contacts 9 and 9^a depend; that is in the direction indicated by the arrow in Fig. 8. So far as has been described there is nothing novel in the parts or in their combination or mode of operation, the same being well understood by those skilled in the art.

We will now proceed to describe a novel element and its novel combination with the previously described elements, whereby new results are accomplished or old results are obtained in a better, cheaper and more advantageous manner than heretofore.

15 is a flat insulating ring provided with diametrically spaced internal projections or teeth, of which four, 16, 17, 18 and 19 are shown. The ring 15 is combined or assembled with the rotary switch member 4 by placing the teeth 16 and 17 opposite the depending ends of the contacts 9 and 9^a and then giving the parts a slight motion of rotation. This brings the teeth or projections

16 and 17 under the contacts and the teeth or projections 18 and 19 in abutment with the offsets 10. Thus when the rotary member is driven in the direction shown by the arrow 5 in Fig. 8, the teeth 18 and 19 abut upon the offsets 10 and so position the teeth 16 and 17, under the ends of the contact arms 9 and 9^a. It will also be observed that the rim of the part 13 of the rotary member overlies the ring 15, and so holds it in one direction. 10 The ring 15 is somewhat larger than the periphery of the crown-tooth member, but its projections or teeth support it or afford means for supporting it in respect to the 15 crown-tooth member. The ring 15 thus mounted, while loose and capable of some play, is nevertheless kept in its proper position by the combined action of the teeth 18 and 19 and the spring pressed elements be- 20 tween which it is interposed; that is, the rotary and stationary parts of the switch. At the same time the contacts 9 and 9^a are exposed when viewed from their outside edges as well as when viewed from their 25 faces and the projections 16 and 17 are in proper position for interrupting or opposing the formation of arcs when the contacts 9 and 9^a leave the fixed contacts 3 and spring into off-position.

30 While we have described the best embodiment of our invention known to us at the present time, still departures may be made in details without departing from the spirit of the invention, hence the latter is not limited as to such matters nor in any way further than the prior state of the art and the appended claims may require.

What we claim is:

1. In an electric switch the combination 40 of a fixed crown tooth member, and a rotary switch member spring-pressed in respect to the crown tooth member and provided with depending contacts coöperating with the teeth of said member, and a flat insulating 45 ring loosely mounted in respect to said members and provided with internal teeth of

which some underlie the contacts and serve to oppose or break arcs and of which others abut on the roots of the contacts to position the first mentioned teeth, substantially as de- 50 scribed.

2. In an electric switch the combination of a fixed crown tooth member and a rotary switch member spring-pressed in respect to the crown tooth member and provided with 55 depending contacts coöperating with the teeth of said members, and a flat insulating ring encircling the contacts of the crown tooth member and loosely mounted in respect to said members and provided with 60 internal teeth of which some underlie the contacts and serve to oppose or break arcs and of which others abut on the roots of the contacts to position the first mentioned teeth, substantially as described. 65

3. In an electric switch the combination of a rotary element provided with depending contacts and with offsets, and a flat insulating ring loosely mounted in respect to said member and provided with internal teeth of 70 which some underlie the contacts and serve to oppose or break arcs and of which others abut on the offsets to position the first mentioned teeth, substantially as described.

4. In an electric switch the combination of 75 a rotary element comprising a hub having diametrically offset arms provided with depending contacts, an insulating disk notched for the passage of said arms and crimped to the hub, and an insulating ring loosely abut- 80 ting on said disk and provided with internal teeth of which some underlie the contacts and of which some abut on said arms to position the first mentioned teeth when the disk is rotated. 85

In testimony whereof we have hereunto signed our names.

SHIRAS MORRIS.
MONROE GUETT.
